OTHER PUBLICATIONS

Commonly assigned U.S. Appl. No. 29/595,795, filed Mar. 2, 2017, entitled CHAIR.

Primary Examiner — Karen S Acker

(74) *Attorney, Agent, or Firm* — Gardner, Linn, Burkhart & Ondersma LLP

(57) **CLAIM**

The ornamental design for a chair, substantially as shown and described.

DESCRIPTION

FIG. 1 is a perspective view of a chair according to a first embodiment of the present invention;

FIG. 2 is a front elevation view of the chair in FIG. 1;

FIG. 3 is a right-side elevation view of the chair in FIG. 1;

FIG. 4 is a rear elevation view of the chair in FIG. 1;

FIG. 5 is a left-side elevation view of the chair in FIG. 1;

FIG. 6 is a top plan view of the chair in FIG. 1;

FIG. 7 is a bottom plan view of the chair in FIG. 1;

FIG. 8 is a perspective view of a chair according to a second embodiment of the present invention;

FIG. 9 is a front elevation view of the chair in FIG. 8;

FIG. 10 is a right-side elevation view of the chair in FIG. 8;

FIG. 11 is a rear elevation view of the chair in FIG. 8;

FIG. 12 is a left-side elevation view of the chair in FIG. 8;

FIG. 13 is a top plan view of the chair in FIG. 8; and,

FIG. 14 is a bottom plan view of the chair in FIG. 8.

The broken lines in the drawings depict environmental subject matter that forms no part of the claimed design.

1 Claim, 8 Drawing Sheets
